CLAIM

The ornamental design for a toaster as shown and described.

DESCRIPTION

FIG. 1 is a perspective view of a toaster;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken dashed and dash-dot lines showing of various portions and other elements in the Figures are for the purpose of illustrating unclaimed portions and form no part of the claimed design.

1 Claim, 7 Drawing Sheets# US D1,113,323 S
